CLAIM

We claim the ornamental design for icon on a portion of a
vehicle display unit used in a global warning anti-collision
system or similar article, as shown.

DESCRIPTION

FIG. 1 is a front view of an icon on a portion of a vehicle
display unit used in a global warning anti-collision system or
similar article showing our new design;

FIG. 2 is a second embodiment thereof; and,

FIG. 3 is a third embodiment thereof.

The broken line drawing in all views of a portion of a vehicle
display is for illustrative purposes only and forms no part of
the claimed design.
